F. C. REID AND T. TAYLOR,
HOSE UNCOUPLING DEVICE,
APPLICATION FILED JULY 9, 1920.

1,368,656.

Patented Feb. 15, 1921.

FIG. 1.

FIG. 2.

INVENTOR
Frederick Charles Reid,
Thomas Taylor.

BY ATTYS.

UNITED STATES PATENT OFFICE.

FREDERICK CHARLES REID AND THOMAS TAYLOR, OF VANCOUVER, BRITISH COLUMBIA, CANADA.

HOSE-UNCOUPLING DEVICE.

1,368,656.

Specification of Letters Patent.

Patented Feb. 15, 1921.

Application filed July 9, 1920. Serial No. 394,869.

To all whom it may concern:

Be it known that we, FREDERICK CHARLES REID and THOMAS TAYLOR, both subjects of the King of Great Britain, and residents, respectively, of the city of Vancouver and the municipality of Burnaby, in the Province of British Columbia, Canada, have invented certain new and useful Improvements in Hose-Uncoupling Devices, of which the following is a specification.

Our invention relates to improvements in hose uncoupling devices, and the object of our invention is to provide a device of this nature by means of which the air brake hose between railway cars may be automatically uncoupled coincidently with the uncoupling of the car coupler lock in a simple, practical, and efficient manner by an operator standing on the outside of the cars, thus eliminating entirely the element of personal danger and at the same time avoiding the risk of breaking or tearing the hose which is always present when the same is uncoupled by pulling it apart by the operation of the cars themselves.

We attain this object by the construction illustrated in the accompanying drawing in which—

Figure 1 is a side view illustrating the practical application of our invention.

Fig. 2 is a perspective view of the device.

Similar figures of reference indicate similar parts in the views.

1 indicates the car coupler lock, as found in railway cars at the present time, the pin 2 of which is withdrawn when uncoupling the lock by the operation of the lever 3 in an upward direction, the lever being actuated by means of a handle 4. 5 indicates the air line found at the ends of the car, the ends of the air line of coupled cars being connected by the air brake hose 6, which as is well-known, consists of two sections coupled at the center. Hitherto it has been the common practice when uncoupling the cars to part the hose by a man stepping between the cars to uncouple it by hand, which is a dangerous operation, and it has also been the practice to part the hose by pulling the cars apart by the engine, which frequently breaks and tears the hose, involving expense for new hose or repairs which adds considerably to the cost of railway operation.

To prevent personal danger on the one hand and to eliminate the damage to the hose on the other we secure to the lever 3 at a suitable point thereon a bracket 7 having an opening 8 through which extends the free end of a lever 9 the opposite end of which is pivotally connected to the end of the car on the pin 10. To the free end of the lever 9 is secured a chain 11 the opposite end of which is passed through a pulley 12 carried by the coupling end of one hose section and secured to the hose at its opposite, or car end, as indicated at 13 in Fig. 2. The length of the chain is such that it will be taut when the hose is coupled in operative position, as shown in Fig. 1.

It will now be seen that on raising the handle 4 to raise the lever 3 to withdraw the coupler pin the lever 9 will be swung upwardly, thus tightening the chain 11 and exerting sufficient strain thereon to part the hose coupling 14 and separate the hose section 6 of the one car from the section 6 of the other car, the effect being to double up the hose automatically in substantially the same manner as it is doubled up manually by an operator between the car when the cars are uncoupled in this fashion. It will, of course, be understood that there is one such device as that above described for each hose section with which the end of each car is provided, as shown in Fig. 1.

From the foregoing it will be evident that we have devised a simple and practical air hose uncoupling means which is of great utility and convenience and enables considerable economy to be effected in train operation.

What we claim as our invention is:

1. The combination with the coupled air brake hose sections of railway cars, of means for uncoupling said sections, comprising a lever fulcrumed on a car end, a pulley mounted on the outer end of the car hose section, a flexible connection extending from the free end of the lever through the pulley and secured to the inner end of the hose section and adapted to be tightened by the raising of the free end of the lever, and means for operating the lever.

2. The combination with the coupled air brake hose sections of railway cars, of means for uncoupling said sections, comprising a lever fulcrumed on a car end, a pulley

mounted on the outer end of the car hose section, a flexible connection extending from the free end of the lever through the pulley and secured to the inner end of the hose section 5 and adapted to be tightened by the raising of the free end of the lever, and a handled rod connected to said lever extending adjacent the outside of the car by means of which said lever may be operated.

10 3. The combination with coupled railway cars, couplers and uncoupling rods therefor, and the coupled air brake hose sections thereof, of means for uncoupling said hose sections coincidently with the uncoupling of the couplers, comprising a slotted bracket secured to the coupler uncoupling rod of one car, a lever passed through the slot in said bracket and fulcrumed at one end on the car end, a pulley mounted on the outer 15 end of the car hose section, and a flexible connection extending from the free end of

the lever through the pulley and connected to the inner end of the hose section, said connection being adapted to be tightened by the raising of the free end of the lever 25 through the operation of the said coupler uncoupling rod when uncoupling the cars.

4. The combination with a car coupler, a coupled air hose line and a car-uncoupling device including an uncoupling lever, of 30 means for uncoupling the air hose simultaneously with the uncoupling of the car comprising a bracket carried by said lever, a second lever passing through said bracket and pivotally secured at one end, and a flexible connection extending between the free 35 end of said lever and said air line.

Signed at Vancouver, B. C., Canada, this 21st day of June, 1920.

FREDERICK CHARLES REID.
THOMAS TAYLOR.
